UNITED STATES PATENT OFFICE.

CHARLES M. STONE, OF LEWISTON, MAINE, ASSIGNOR OF ONE-HALF TO WILLIAM H. PUTNAM, OF LEWISTON, MAINE.

PICKER-STICK FRICTION-BUNTER.

1,341,394.

Specification of Letters Patent. Patented May 25, 1920.

Application filed July 1, 1918. Serial No. 242,889.

To all whom it may concern:

Be it known that I, CHARLES M. STONE, a citizen of the United States, residing at Lewiston, in the county of Androscoggin and State of Maine, have invented certain new and useful Improvements in Picker-Stick Friction-Bunters, of which the following is a specification.

This invention relates to improvements 10 in picker stick bunters and used in place of or additional to the bunters now in use, including the lay at the end of the race. It relates particularly to means for easing the end of the forward throw of the stick, thus 15 preventing injury to the stick and at the same time interfering as little as may be with its return. It is also designed to lessen the vibration of the picker stick, especially after the stick operating cam has ceased to 20 act, and to lessen wear on the picker stick pivot bolt. It is also designed to cause the picker to throw the shuttle straight. It is also designed to provide a picker stick bunter that is little subject to wear, is 25 adjustable and remains adjusted after having been set. It is also designed to prevent the picker stick from flying up after it reaches the forward end of its stroke. The friction bunter can be readily adjusted to cause the 30 picker stick to remain constantly in the center or at one side of the race, as desired.

In the drawing herewith accompanying and forming a part of this application, Figure 1 is an elevation of one end of a lay with 35 my improved friction bunter applied thereto; Fig. 2 is a bottom plan view of Fig. 1; and Fig. 3 is a transverse vertical sectional view of Fig. 1 taken on line X—X looking to the left.

40 The same reference characters indicate like parts in the several figures.

In said drawing 1 is one end of the lay of a loom provided with the usual picker stick race 2 of any usual construction. My improved friction bunter is attached to the outside of the lay, preferably two at each end, one on each side of, but below the race.

45 My improved device consists of a bracket or hanger 3 attached to the lay by means of a bolt 4. The bracket is preferably offset, as seen at 5 and has a downwardly extend-

ing bunter supporting arm 6. To the inside of arm 6 my friction bunter 7 is attached preferably by a screw 8. The bunter is made of a yielding spring plate, preferably of 55 wood, and it is suspended under the lay and directly under the race and its free end is adapted to be adjusted and held by a set screw projecting into the path of the picker stick as it moves forward in the race. The 60 stick thus frictionally engages the face of the bunter plate and the side of the race and is more or less retarded by frictional engagement therewith until it finally comes to a stop, preferably just before it strikes 65 against the lay at the end of the race. In most cases I have found it better to use two similar bunter plates, one on each side of the race, their free ends projecting toward each other. The distance between the bunter 70 plate and the lay or between the two bunter plates, when two are used, can be readily adjusted by set screws 9 to give the proper frictional resistance which can be readily determined by experiment. Washers 13 of leather or other suitable material may be inserted between the ends of the adjusting set screws which tend to lessen the jar and vibration.

75 My invention further consists in the combination in a single integral piece of material of a picker stick friction bunter and a picker stick friction shuttle check and I have illustrated my invention in this form for convenience, the power of attachment 80 being intermediate its ends.

85 It is to be understood, however, that my invention may be embodied in a form having only the bunter friction check, in which case it will be attached to the bracket carrying plate as before.

90 The operation of my bunter check and its adjustment is readily apparent from the drawing and the foregoing description. The picker stick should pass a considerable 95 distance out of contact with the bunter check and then frictionally engage the adjacent faces thereof, and the bunter check should be preferably adjusted so that the resistance to the forward throw of the picker would 100 gradually increase until it just lightly reaches the end of the race, thus obviating

any danger of the breaking of the picker stick by its striking hard against the solid iron at the end of the race.

I claim:

5 A picker check comprising a pair of spring plates arranged to engage opposite sides of a picker stick, said plates being free

at the ends and secured at points that are a greater distance apart than the ends, with means intermediate the ends and the points of attachment for varying the distance between the free ends.

In testimony whereof I affix my signature.

CHARLES M. STONE.
